HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

TILTING CASTING BOX

Application filed October 12, 1926, Serial No. 141,168. Renewed April 17, 1930.

This invention relates to the horizontal type of stereotype plate casting machines in which the core is mounted to rotate on the fixed horizontal axis and the back is arranged to move bodily toward and from the core, usually in a vertical direction.

The principal objects of the invention are to provide a construction by which the back can be tilted outwardly away from the core to facilitate and simplify the insertion of the matrix and its replacement by a new one; to provide this means in a simple form that involves only a few parts, and to arrange the parts in such position that they can be returned to casting position without any adjustments or any uncertainty as to the position of the box at casting time.

Other objects and advantages of the invention will appear hereinafter.

Reference is to be had to the accompanying drawings in which

Fig. 1 is a front view of a casting box constructed in accordance with this invention;

Fig. 2 is an end view of the same shown in casting position; and

Fig. 3 is an end view with the parts positioned for removal or replacement of the matrix.

I have applied the invention to a casting machine comprising a frame 10, a core 11 rotatable on a horizontal shaft 11^a, carried by the frame 10 and a reciprocating back 12. The back is operated by a crank shaft 13 which receives the power from any desired source and has two crank rods 14 which are connected with the back 12. This connection is shown as made through a pair of eccentric pins 15 having arms 16 thereon and adjusting screws 17 adapted to be adjusted from lugs 18 on the frame through which these screws pass. Adjustment of these screws determines the height of the box and secures the perfect fit of the box at both ends against the core and the end rings.

The box is guided to move in a vertical direction by a pair of guides 20 which are pivoted on the concentric portions of the crank shaft 13 and are received between guideways 21 extending vertically downward from the bottom of the casting box 12. These guides

therefore are capable of turning about the concentric portion of the shaft 13. Normally they are held back by strong springs 22 against adjustable stop screws 23 carried by the frame so that they move exactly to vertical position. They perform the function of guiding the box as if they were fixed in this position. However, each one is provided with a turn-buckle 24 pivotally connected with it and adjustably connected with an arm 25 to which the turn-buckle is pivoted. These arms 25 are fixed to a shaft 26 which has an arm 27 swinging it. The turn-buckle and arm form a toggle which, when straightened out, locks the guides back in casting position.

In operation the back is in the position shown in Figs. 1 and 2. The crank shaft 13 is rotated after the casting of the plate to bring the box down to allow the plate to be taken out or discharged in any desired way and then returned to casting position. It will be observed that whenever the box is raised to casting position the matrix clamps 28 are engaged by studs 29 fixed on the frame 10 and forced tightly against the box to hold the edge of the matrix M. When the box is lowered this pressure is released but the clamps remain in place and hold the matrix while the casting is being removed and the operation is repeated over and over.

When it is desired to replace the matrix, remove it, or introduce it in the first place, the shaft 13 is turned so that the cranks as indicated in Fig. 3, pull the box 12 down so that it clears the core. Now the handle 27 is turned to the position shown in Fig. 3 which swings over the whole structure that is pivoted on the shaft 13 in opposition to the two springs 22. Now the matrix can be introduced, replaced, removed, or inspected and then the handle 27 can be swung back. This brings the casting back directly under the rotatable core so that when the shaft 13 is rotated a half revolution, the casting box will be closed ready for receiving the metal.

This invention eliminates difficulties which are now present in this type of casting machine because it makes the insertion and removal of the matrix simple and easy with no

parts in the way to obstruct. At the same time no material complications are introduced and the machine is as rigid and the parts close together as perfectly as if this feature were not present.

5 The arms 25 and turn buckles 24 constitute toggles which, when straightened out, lock the back in its rearmost casting position even independently of the springs 24. Thus these 10 springs are not depended on to hold the parts firmly in position for casting. The toggles also hold the back in the position shown in Fig. 3, as they are then on dead centers.

Although I have illustrated and described 15 only one form of the invention I am aware of the fact that modifications can be made therein by any person skilled in the art without departing from the scope of the invention as expressed in the claims.

20 Therefore I do not wish to be limited to the details shown, but what I do claim is:

1. In a stereotype plate casting device, the combination with a core, of a reciprocable concave back cooperating with the core and 25 having means for holding the matrix therein, said back being mounted to swing on a horizontal axis at a distance beyond the convex side of the back to a position at the side of the core for facilitating the positioning of the 30 matrix.

2. In a stereotype plate casting machine, the combination with a core, of a back, means for reciprocating the back, guides for guiding the back to move in straight lines during 35 its reciprocation, said guides being pivotally mounted, whereby the guides may be swung to one side to bring the casting box into a position at the side of the core.

3. In a stereotype plate casting machine, 40 the combination with a core, of a back, a crank shaft, means for connecting the back to the crank shaft for reciprocating the back thereby, guides for guiding the back to move in straight lines during its reciprocation, said 45 guides being pivotally mounted on concentric parts of said crank shaft, whereby the guides may be swung to one side to bring the casting box into a position at the side of the core.

4. In a casting machine, the combination 50 with a mold part, of a crank shaft, a pair of crank rods connected with the crank shaft and with the mold part for reciprocating the mold part, a pair of guides for said mold part pivoted on the crank shaft, means for swinging 55 said guides about the crank shaft, whereby the mold part will be moved laterally, and yielding means for normally holding the mold part in casting position.

5. In a stereotype plate casting device, the 60 combination with a rotatable core, of a back, a crank shaft for operating the back, a pair of guides for the back pivotally mounted on the crank shaft, a pair of toggle levers connected with the guides, a shaft on which the 65 toggle levers are mounted, whereby the turn

of said shaft will move the back toward and from their casting position, and stops for limiting the backward motion of the guides to bring the back to casting position.

6. In a stereotype plate casting device, the 70 combination with a core, of a back, means for operating the back, guides for the back pivotally mounted, toggle levers connected with the guides, and a shaft on which the toggle levers are mounted, whereby the turn of said 75 shaft will move the guides toward and from their guiding position, said toggles being arranged to hold the guides and back in both extreme positions.

7. In a stereotype plate casting device, the 80 combination with a rotatable core, of a back, a crank shaft for operating the back, means for adjusting the distance between the crank shaft and the back, a pair of guides for the back pivotally mounted on the crank shaft, 85 a pair of toggle levers connected with the guides, and a shaft on which the toggle levers are mounted, whereby the turn of said shaft will move the back toward and from their casting position.

8. In a casting machine, the combination 90 with a mold part, of a crank shaft, a pair of crank rods connected with the crank shaft and with the mold part for reciprocating the mold part, and a pair of guides for said mold 95 part pivoted on the crank shaft.

9. In a stereotype plate casting machine, 100 the combination with a core, of a back, means for reciprocating the back, guides for guiding the back to move during its reciprocation, said guides being pivotally mounted, whereby the guides may be swung to one side to bring the casting box into a position at the side of the core.

In testimony whereof I have hereunto affixed my signature.

HENRY A. WISE WOOD.
